UNITED STATES PATENT OFFICE.

EDMUND K. BAKER, OF SPRINGFIELD, MASSACHUSETTS.

CAP FOR SHEET-METAL PAINT-CANS.

SPECIFICATION forming part of Letters Patent No. 323,623, dated August 4, 1885.

Application filed June 22, 1885. (No model.)

To all whom it may concern:

Be it known that I, EDMUND K. BAKER, a citizen of the United States, residing at Springfield, in the county of Hampden and 5 State of Massachusetts, have invented new and useful Improvements in Caps for Sheet-Metal Paint-Cans, of which the following is a specification.

This invention relates to improvements in 10 sheet-metal cans, the object being to provide for cans which are adapted to hold paint and similar substances, and which have through one end an opening for inserting and removing the contents of the can, an improved device 15 for closing said opening hermetically and for indicating the color of the contents of the can.

In the drawings forming part of this specification, Figure 1 is a sectional view of the 2 end and a portion of the sides of a tin or sheet - metal can, and Fig. 2 is a view in transverse section of a device for closing the opening in the end of the can, Fig. 1, embodying my improvements. Fig. 3 is a plan 25 view and a sectional edge projection of the base-plate of said closing device. Fig. 4 illustrates a glass disk, and Fig. 5 is a plan view of the perforated top plate of the closing device.

30 In the drawings, *e e* indicate the sides of a metal can, and *a* the top thereof, having a depressed central portion, *b*, and through the latter a circular opening, *z*, a shoulder, *n*, being formed around said opening, said shoulder being sunk below the general level of the 35 top of the can a distance about equal to the thickness of the closing device, hereinafter described. The above-referred-to opening *z* is of suitable diameter to admit of filling the 40 can therethrough with paint or similar substance.

The cap or closing device for the opening *z* in the end of the can consists of three parts—viz., the base-plate *c*, the glass disk 45 *h*, and the perforated top plate, *o*—all united, as hereinafter set forth, to form the complete cap or closing device for the can, a sectional view of which is shown in Fig. 2.

Metal cans of this class, which are used 50 for putting up paint in, are often provided with some means for indicating on the outside thereof the color or quality of the contents; and, as above mentioned, one object

of this invention is to provide improved means of said indication, and to this end 55 said cap or closing device is constructed and applied to the can as follows: The base-plate *c* is first made in the form shown in Fig. 3, that is to say, with a depressed central portion, *v*, and an upwardly-turned border, *x*, and the surface of said plate within said depressed part is then coated with paint, *d*, of the color and quality of that with which the can is filled, and for whose cap it is to serve as a part. Said paint having been applied to 65 the base-plate, the glass disk *h* is placed over the painted surface thereof, and the perforated top plate, *o*, so formed, as shown in Fig. 2, that its inner edge bears on the glass *h* and holds it down with more or less spring 70 force, is then placed on plate *c*, and then the border *x* of the latter is bent inward upon the plate *o*, firmly locking said two plates and the glass disk together, as shown in Fig. 2.

The diameter of the cap or closing device 75 just described is such that it fits in the aforesaid depression *b* in the end of the can so that the upper side of the top plate, *o*, is about in the same plane as the end *a* of the can, and the latter having been filled with paint, as 80 aforesaid, said cap is soldered around its border to the can, hermetically closing the orifice *z*, but showing through the glass *h* the coat of paint *d* of like color to that in the can, as above described. Thus said cap is 85 formed, embracing the base-plate *c*, having the coat *d* of paint on its inner depressed surface part, the clear glass disk *h*, through which can be seen the coating *d* on the base-plate, and the top plate, *o*, all secured together, as above described.

What I claim as my invention is—

A compound cap for closing the orifice in sheet-metal paint-cans, consisting of the centrally-depressed circular metallic base-plate *c*, 95 having the upturned border *x*, and having applied to said depressed portion a coat, *d*, of paint, the perforated metallic top plate, *o*, fitting within the border *x* of plate *c*, and the clear glass disk *h*, interposed between said two 100 plates, all combined and united substantially as set forth.

EDMUND K. BAKER.
